Des. 196,410
Patented Sept. 24, 1963

196,410

PORTABLE OXYGEN DISPENSER

Donald L. Wicks, Minneapolis, Minn., assignor, by mesne assignments, to Continental Research, Inc., Minneapolis, Minn., a corporation of Minnesota

Filed Nov. 13, 1961, Ser. No. 67,505

Term of patent 14 years

(Cl. D83—1)

Fig. 1.

Fig. 2.

Fig. 3.

FIG. 1 is a plan view in operation position of a portable oxygen dispenser showing my new design and as seen in the direction of the arrows 1—1 of FIG. 2;

FIG. 2 is a side elevational view;

FIG. 3 is an end view thereof as seen in the direction of the arrows 3—3 of FIG. 2 with the support member fragmentarily shown for convenience of illustration; and

FIG. 4 is an enlarged perspective view thereof.

The portions shown in broken lines are for illustrative purposes only.

I claim:

The ornamental design for a portable oxygen dispenser, as shown and described.
